UNITED STATES PATENT OFFICE.

ALMON E. NORRIS, OF BROOKLINE, MASSACHUSETTS.

HOISTING APPARATUS.

Application filed April 10, 1920. Serial No. 372,936.

To all whom it may concern:

Be it known that I, ALMON E. NORRIS, a citizen of the United States, and a resident of Brookline, county of Norfolk, and State 5 of Massachusetts, have invented an Improvement in Hoisting Apparatus, of which the following description, in connection with the accompanying drawings, is a specification, like characters on the drawings representing like parts.

This invention relates to improvements in hoisting and conveying apparatus and, among other objects, provides improved means for facilitating the control of such 15 apparatus.

Herein there is disclosed an embodiment of the invention as applied to the control of a trolley-supported bucket or grab as employed in connection with a self-propelled 20 bridge, but the invention is applicable also to hoisting apparatus employed in connection with other structures and other forms of load-carrying devices.

This application is a division of my prior 25 co-pending application Ser. No. 69879, filed Jan. 3, 1916.

The invention will be best understood by reference to the following description when taken in connection with the accompanying 30 illustration of one specific embodiment thereof, while its scope will be more particularly pointed out in the appended claims.

In the drawings:

Figure 1 is a side elevation showing the 35 structure of a bridge selected for illustration as embodying one form of the invention;

Fig. 2 is a plan showing the rope-winding drums and devices cooperating therewith for 40 controlling the cables for the trolley and the grab;

Fig. 3 shows in sectional plan and on an enlarged scale the governor-controlled brake valve and the switch for throwing into operation the regenerative braking.

Fig. 4 shows more or less diagrammatically and in side elevation the opening and closing drums and the hoisting drum, with the controlling brakes therefor, together 50 with a controlling stand and pressure fluid conducting pipes connected to the brake-controlling cylinders;

Fig. 5 shows on an enlarged scale and in horizontal section the governor-controlled

brake valve and the switch in a different 55 position from that shown in Fig. 3;

Fig. 6 is a view in side elevation of the parts shown in Fig. 5; and

Fig. 7 is a wiring diagram showing the electrical connections for the primary and 60 secondary panels of the master controller for the hoisting motor and the electrical connections between the governor and said controller.

Referring to the drawings, the invention 65 is therein shown for illustrative purposes as applied to a hoisting and conveying bridge structure (Fig. 1) which supports an overhead trackway 1, one end of which is sustained by a boom 3. A trolley carriage 70 5 is adapted to run on said trackway and support a grab or bucket 7 of the well-known clamshell type.

The bucket as shown is provided with a holding or hoisting cable 9 and also an 75 opening and closing cable 11, the latter for opening and closing its jaws. The holding cable is connected to be wound about or unwound from the holding drum 13, whence it extends over the guide sheaves 15 and 17 to 80 one end of the trackway, thence to the trolley carriage and the bucket and thence to a dead end or fixed anchoring point at the opposite end of the trackway.

The opening and closing cable likewise is 85 connected to the opening and closing drum 19, whence it extends over suitable guide sheaves, including the sheave 21, to one end of the trackway, thence to the trolley and the bucket, and thence to a dead end at the 90 opposite end of the trackway. The trolley is traversed by means of an endless trolley rope 23 which passes around the trolley winding drum 25 and thence over guide sheaves at opposite ends of the trackway 95 and thence to the trolley carriage 5 to which its ends are fixedly secured.

The trolley winding drum may be driven by any suitable means, there being employed for that purpose the electric motor 100 30; but since the propelling mechanism is not necessary to an understanding of the present invention, no further description of the same is necessary.

Referring now to the grab hoisting and 105 opening mechanism, the opening and closing drum 19 is adapted to be connected by a clutch 31 with a gear 33; and the holding

drum 13 is adapted to be connected by a similar clutch 35 to a gear 37, the gears 33 and 37 being in mesh with and adapted to be driven by an intermediate pinion 39 fast on the shaft 41 driven by the electric motor 43. The devices for operating the clutches to connect the two drums to or disconnect them from the driving gears may be of any usual type and their specific construction is immaterial to the present invention, it being sufficient to state that they are herein controlled by pressure fluid admitted through the respective pipes 45 and 47 and controlled from the operator's stand at 49 (Fig. 4).

To hold the bucket, the holding drum 13 may be provided with means which automatically prevents the unwinding movement of the drum except when desired by the operator, such means being herein comprehended in the form of a brake which automatically prevents unwinding movement of the drum except when released, while permitting at all times the winding on movement thereof. As shown herein, the drum 13 has a large brake wheel 51 (Figs. 2 and 4) fixed thereto at the end opposite the clutch 35, said wheel being encircled by a brake band 53 connected to a brake lever 55 and a link 56 of a general construction similar to that disclosed in Letters Patent 1,123,786, granted to me Jan. 5, 1915.

When the drum tends to unwind the cable by turning in a contraclockwise direction 35 (Fig. 4), the link, which is normally positioned by a spring 57, is drawn out by reason of the friction on the band. This enforced movement of the link automatically closes and applies the brake irrespective of 40 a releasing movement of the brake lever 55. Rotation of the drum 13 in the opposite direction draws the link down toward the center line passing from the axis of the hub to the point of pivotal support of the 45 link, thereby automatically opening or unclasp the band and leaving the drum at all times free for rotation in that direction.

The brake may also be positively released for movement in a contraclockwise direction (Fig. 4) by a releasing movement of the lever 55. To accomplish this, said lever may be connected by a link 59 with one arm of a bellcrank 61, the other arm whereof is pivotally connected to the stem 63 of a piston 55 ton in a cylinder 65 having a pipe 67 (Fig. 4) connected thereto for conducting pressure fluid to the cylinder from a pressure fluid supply. The admission of pressure fluid to the cylinder is under the control of 60 the operator at the controlling stand 49, so that while the brake normally prevents reverse or unwinding movement of the holding drum and at all times permits the winding movement thereof, it may be released at 65 will to permit the lowering of the grab.

To assist in stopping the holding drum motor and to prevent reversal of the motor shaft, a brake may be applied to the motor shaft 41 which is geared to the drum. This brake comprises a wheel 69 encircled by a 70 brake band 71 connected to a brake lever 73 by a link 75 constructed and operating in a manner similar to that described for the holding drum brake. To positively release the brake, there may be provided a 75 releasing lever 77 connected by a stem 79 with a piston in a cylinder 81, the latter connected by a pipe 83 with a source of pressure fluid as is more fully hereinafter described.

Any suitable arrangement of controlling levers may be employed but herein I have provided for the controlling stand 49 two such levers 85 and 87. The lever 85 is connected to the shaft of a master controller 85 capable of starting the trolley motor in either direction at will, while the lever 87 is connected to a master controller which exercises a suitable control over the hoisting motor 43 as will more fully appear. 90 Both levers are connected to exercise a co-operative control over the various valve devices which are employed for admitting fluid pressure to the various clutch and brake operating units at the hoisting drums. Such devices are described in detail in my aforesaid prior application, Ser. No. 69,879, but the details thereof are not necessary to an understanding of the present invention, it being sufficient to state that through the 100 control of the lever 87 pressure fluid to control the brake cylinders 65 and 81 may be admitted to or exhausted from a pipe 89 and, under the control of the governor-controlled brake valve hereinafter described, admitted to or exhausted from the brake cylinders themselves.

Referring now to the control of the lowering of the grab by regenerative braking, when the lever 87 is shifted to release the 110 brakes and permit the lowering of the grab, the unwinding of the cables from the holding and opening and closing drums reverses the motor 43 and when the latter attains synchronous speed its circuit is automatically closed and the motor is operated regeneratively, thereby returning power to the line from which it receives its circuit.

The work of this regeneration serves to check or limit the speed of fall of the grab 120 and to maintain a substantially constant lowering speed therefor. To produce this regeneration, the holding motor may be provided with a governor 91 (Figs. 2, 3, 5 and 6) comprising a head fixed to the outer 125 end of the holding motor shaft 41 referred to, and having segments 95 pivoted thereto. These segments have inwardly projecting arms 97 pivoted to a ring 99 fast on a spindle 101 adapted to slide in a projection on 130

said head. The spindle has a rounded end seated in a similarly shaped depression 103 in a bar 105. One end of said bar is suitably connected to one end of a rod 107, the opposite end of which is adapted to slide in a plug 109 of a valve casing 111 mounted on a bracket 113 on a standard adjacent to the holding motor shaft 41. This casing contains a valve 115 normally urged against 10 said plug by a helical spring 117 in a casing 119 tapped into one end of the valve casing. The tension of said spring may be varied by an adjusting screw 121.

The valve casing is provided with a port 123 connected to the pipe 89 referred to for conducting pressure fluid from the control stand. The valve casing is also provided with a port 125 communicating with a pipe 127, referred to, leading to the pipes 67 and 83 which are connected to the controlling cylinders for the brakes for the holding drum and its motor. The valve casing is also provided with a port 129 communicating with an exhaust pipe 131.

25 The spindle bar 105 is also connected to one end of a plunger 133 adapted to slide in a plug 135 and a spring casing 137 on upright members 139 rising from the bracket 113 referred to. A disc 141 of insulation 30 material is mounted fast on said plunger intermediate its ends and carries a contact ring 143 adapted for engagement with contact fingers 145 mounted on an insulation bar 147 secured to one of the upright members 139. The plunger 133 is normally urged toward the governor by a spring 149 contained in the casing 137, the tension of which may be varied by an adjusting screw 151.

40 When the hoisting motor shaft is rotated by the unwinding of the drums, the governor segments 95 will tend to fly outward by centrifugal force from their position shown in Fig. 5 to their position shown

45 in Fig. 3. This will cause the spindle 101 to slide outward and press the bar 105 on the valve spindle 107 and contact plunger 133 against the resistance of their springs. The spindle is connected with the bar at one 50 side of the center of the bar so that it operates with greater mechanical advantage on the contact plunger than on the valve spindle. Consequently, the governor spindle in moving outward will first thrust the

55 contact ring 143 into engagement with the contact fingers 145, and may under certain conditions then shift the brake-controlling valve 115 toward the right of Figs. 3 and 5 to apply the holding drum and motor shaft 60 brakes. The connecting of the contact ring with the contact fingers completes a circuit to be described for the holding drum motor.

As soon as the motor speed is above synchronous speed the regenerative braking obtained by the motor will be effective to

sufficiently limit the speed of fall of the grab and the spindle bar 105 will remain in its position shown in Fig. 3, holding the contact ring 143 against the finger contacts 145 and completing the circuit to said motor. 70 If, however, the regenerative braking should fail to sufficiently limit the fall of the grab, the speed of the hoisting motor will increase, thereby increasing the speed of rotation of the governor and causing the segments 95 75 of the latter to fly further outward. This will thrust the spindle bar 105 from its position shown in full lines in Fig. 3 to its position shown in dotted lines in said figure, thereby shifting the valve 115 to the right 80 (Figs. 3 and 5) and placing the pipe 127 leading to the automatic brakes of the holding drum and its motor shaft into communication with the exhaust pipe 131. This will permit the springs of said brakes to become effective to apply the same and retard the fall of and bring the grab to rest.

It will be understood that the governor-controlled valve is normally in the position shown in Figs. 3 and 5, thereby placing the pipe 127 leading to the brake-controlling cylinders of the holding drum and its motor in communication with the pipe 89 leading from the interlock valve.

The master speed controller for the alternating current motor for the holding drum may be in its broad aspect of usual construction and therefore need not be described in detail herein excepting in so far as it may be necessary to explain the electrical connections of the governor-controlled switch therewith.

Referring to Fig. 7, there is shown a development of the master controller cylinder contacts together with stationary contacts 105 cooperating therewith.

P' , P^2 , P^3 , designate the three-phase primary conductors leading to the alternating current hoist motor 43. The conductor P' leads directly to said motor, while the conductors P^2 and P^3 are interrupted by a switch 161 adapted to be closed to complete the primary circuit for forward driving of the motor to hoist the grab and by a switch 163 adapted to be closed to complete the primary circuit to the motor for reversing the same. To close the forward switch 161 it has an armature 165 connected thereto adapted to be attracted by a magnetic coil 167.

The circuit for energizing the forward switch coil 167 comprises a conductor 173 tapped from the primary conductor P^3 and connected by a switch 175 with a conductor 177 leading to a stationary contact 179 at 125 the master controller. This contact is adapted to be connected by a bridge contact 181 on the controller cylinder with a stationary contact 183. The latter is connected by a conductor 185 with a fixed contact 187 at 130

the reverse switch 163 and adapted to be connected by a bridge contact 189 with a fixed contact 191 by the reverse switch when the latter is open. The fixed contact 191 is connected by a conductor 193 with a fixed contact 195 at the forward switch 161, said fixed contact 195 being connected by a conductor 197 with the coil magnet 167 for closing the forward switch. Said coil is connected by a conductor 199 with a conductor 201 through a switch 203 controlled by an overload coil 205. The conductor 201 is connected to a conductor 207 through a switch 209 controlled by an overload coil 211. These overload switches and coils are of usual construction and need not be further referred to herein. The conductor 207 is connected by the switch 213 with the conductor 215 leading to the primary conductor P^2 .

From the above description it will be apparent that when the controller cylinder is shifted to the right the bridge contact 181 will connect the stationary contacts 179 and 183 and thereby complete the circuit just described to the coil magnet 167. This will energize said coil and shift the forward switch 161 to the left (Fig. 7), thereby completing the circuit through the primary conductors P^2 and P^3 to the alternating current motor 43, and rotating the same in a direction for hoisting the grab.

As the controller cylinder is shifted further to the right, bridged contact segments 217 on the cylinder will connect a stationary contact 219 with a stationary contact 221 and thereby cut out some of the resistances 223 on the secondary panel. As the controller cylinder is shifted further to the right, contact segments 225 are progressively brought into engagement with stationary contacts 227, thereby progressively cutting out additional resistances and increasing the speed of the motor. Since these resistances and the circuits therefor are of usual construction, it is thought unnecessary to describe them further herein.

The circuit for energizing the reverse switch coil 171 comprises a bridge contact 229 on the controller cylinder for connecting the stationary contact 179 referred to with a stationary contact 231. The latter is connected by a conductor 233 with one of the finger contacts 145 which, as stated, is adapted to be connected by the governor-actuated ring contact 143 with a finger contact 145. The latter contact is connected by a conductor 234 with a fixed contact 235 at the forward switch 161 and adapted to be connected by a bridge contact 237 with a fixed contact 239 by the forward switch when the latter is open. The fixed contact 239 is connected by a conductor 241 with the reverse switch-actuating coil 171 referred to. This coil is connected by a conductor 243 with the magnetic coil 167 for the forward switch.

As stated, this coil is connected through the conductors 199, 201, 207 and 215 with the primary conductor P^2 .

When the controller cylinder is shifted to the left (Fig. 7), the bridged contacts 229 will connect the stationary contact 179 and 231 and the circuit will be completed for energizing the reverse switch magnetic coil 171 with the exception at the point where the circuit is broken by the governor-controlled switch 143. When the motor is reversed by the drop of the grab and brought above synchronous speed, the governor will automatically close the switch 143 and complete the circuit to the reverse switch coil 171, thereby causing the reverse switch 163 to complete the circuit through the primary conductors P^2 and P^3 to the motor. The regenerative braking will now commence.

The usual current-limiting coils 245 and 85 their circuits and switches may be provided and need not be referred to further herein.

When the cylinder is shifted to the left as described, a series of resistance segments 247 will be brought into engagement with 90 the stationary contacts 219, 221 and 227, thereby cutting out all of the resistances 223 referred to.

As long as the speed of the motor is maintained above synchronism by the fall of the 95 grab, it will continue to act with regenerative braking effect, but if for any reason the speed of the motor should increase beyond this point, as for example on failure of the current, then it will cease to act with regenerative braking effect and the governor will shift the valve 115 and permit the pressure fluid on the brakes to exhaust, thereby permitting the automatic brakes to apply to 100 check the lowering of the grab and arrest 105 the same.

It is desired at times to reverse the motor and enable a few reverse turns to be imparted to the winding drums to "kick off" the cables therefrom to initiate and accelerate the fall of the grab or to slacken the cables as desired. To accomplish this the controller cylinder is provided with a contact 249 adapted to be connected with a stationary contact 251 when the cylinder is 115 shifted to the extreme left, said contact being connected by a conductor 253 with the conductor 234 leading to the magnet coil 171 for controlling the reverse switch 163. This will serve as a shunt across the conductors 233 and 234 leading to the governor-controlled switch and complete the circuit to the coil 171 and close the reverse switch 163 independently of the governor-controlled switch.

While I have herein shown and described for purposes of illustration one specific embodiment of the invention, it is to be understood that the same is not limited to the mechanical details or the form of relative ar- 130

angement of parts herein disclosed, but that extensive deviations therefrom may be made without departing from the spirit thereof.

Claims:

5. 1. A hoisting apparatus comprising, in combination, a grab, a cable therefor, a drum for said cable, a motor adapted when rotated in one direction to wind in said cable, and when turned in the opposite direction to produce regenerative braking, a governor rotated by said motor, and means controlled by said governor for automatically completing a circuit thereto for initiating such braking.
10. 2. A hoisting apparatus comprising, in combination, a grab, a holding cable therefor, a drum for said cable, a motor connected to said drum, an alternating current motor for driving said drum, a governor driven by said motor, and electrical connections for said motor and governor including a switch automatically closed by said governor for limiting the fall of the grab by regenerative braking on reversal of said motor at synchronous speed.
15. 3. A hoisting apparatus comprising, in combination, a grab, a drum, a cable connecting said grab with said drum, an alternating current motor, means connecting said motor with said drum, a governor driven by said motor, and a switch actuated by said governor when said motor attains a reverse synchronous speed to close the circuit to said motor and regenerate the feed line thereto.
20. 4. A hoisting apparatus comprising, in combination, a carrier, a drum, a cable connecting said carrier with said drum, a motor for the latter, an automatic brake for said drum, pressure fluid operated means for releasing said brake, a governor driven by said motor, means controlled by said governor for completing the circuit to said motor for checking the fall of the carrier by regenerative braking, and means for automatically rendering said brake effective to resume the retarding of the fall of said carrier if the motor attains an excessive speed.
25. 5. A hoisting apparatus comprising, in combination, a carrier, a drum, a cable connecting said carrier with said drum, an alternating current motor connected to said drum for driving the same to hoist said carrier, an automatic brake for said drum, means for releasing said brake to permit the drop of said carrier and the reversal of said motor, and means for controlling the circuit to said motor having provision for automatically regenerating the feed line thereof when the motor has been brought up to synchronous speed by the drop of said carrier.
30. 6. A hoisting apparatus comprising, in combination, a carrier, a drum, a cable connecting the same, an alternating current motor for rotating said drum to hoist said carrier, an automatic brake for checking the initial drop of said carrier, and means for automatically completing the circuit to said motor when it attains a predetermined reverse speed to regenerate the feed line to said motor and relieve said automatic brake of the work of limiting the speed of drop of the carrier.
35. 7. A hoisting apparatus comprising, in combination, a grab, a winding drum, a cable connecting the same, and an alternating current motor rotatable in one direction for hoisting the grab and having provision on reverse rotation thereof for limiting the fall of the grab to a substantially constant speed.
40. 8. A hoisting apparatus comprising, in combination, a carrier, a winding drum, a cable connecting the same, an alternating current motor connected to said drum, electrical means for said motor including a controller having means for causing said motor to rotate in one direction to hoist said carrier, means for causing a few reverse turns of said motor to assist the initial drop of the carrier, and means for automatically completing the circuit to said motor when it attains synchronous speed to regenerate the line of feed thereof and thereby limit the speed of fall of the carrier.
45. 9. A hoisting apparatus comprising, in combination, a carrier, a winding drum, a cable connecting the same, an alternating current motor rotatable in one direction for hoisting the carrier and in the opposite direction by the fall of the carrier, an automatic brake for said drum, pressure fluid controlling means including a valve for admitting pressure to release said brake, a governor driven by said motor for automatically completing the circuit thereto to regenerate its feed line when said motor attains synchronous speed, and means controlled by said governor for shifting said brake controlling valve to release the pressure on said brake and permit said brake to apply itself to retard the drop of the carrier if the motor attains a speed greater than synchronous.
50. 10. A hoisting apparatus comprising, in combination, a carrier, a winding drum, a cable connecting the same, an alternating current motor rotatable in one direction to hoist said carrier and in the opposite direction by the drop of said carrier, an automatic brake for said drum, means for applying pressure fluid to release said brake including a valve, a circuit for said motor including a switch, and a governor driven by said motor having provision for automatically closing said switch to produce regenerative braking on synchronous reverse speed of said motor and for automatically shifting said valve to release pressure from said brake when said motor attains a higher speed.

- 6
11. A hoisting apparatus comprising, in combination, a carrier, a winding drum, a cable connecting the same, an alternating current motor rotatable in one direction for hoisting the carrier and in the opposite direction by the drop of the carrier, an automatic brake for said drum, means for applying pressure fluid to said brake to release the same including a valve, a circuit for said motor including a switch, a governor driven by said motor, and means connecting said governor with said switch and valve for automatically operating the same. 70
12. A hoisting apparatus comprising, in combination, a carrier, a winding drum, a cable connecting the same, driving means for said drum for hoisting the carrier, a brake for said drum, and means operating through said driving means for automatically limiting the lowering speed of the carrier following release of said brake. 75
13. A hoisting apparatus comprising, in combination, a carrier 7, a cable 9 therefor, a drum 13 for said cable, an alternating current motor 85, a governor 91 driven by said motor, and a switch 141 actuated by said governor for completing the circuit to said motor when the latter attains a predetermined speed to retard the lowering of the carrier by regenerative braking. 80
14. In a hoisting apparatus, the combination with a carrier of a drum and cable for hoisting the same, an electric motor for rotating said drum, a brake for holding said carrier in elevated position, means cooperating with said motor on release of said brake and reversal of said motor automatically to produce regenerative braking to limit the lowering speed of said carrier, and means for automatically applying said brake if said motor exceeds its regenerative braking speed. 85
15. In a hoisting apparatus, the combination with a carrier of a drum and cable for hoisting the same, an electric motor for rotating said drum, a circuit and electrical connections for said motor, a switch in said circuit, and a governor actuated by said motor for automatically operating said switch to complete said circuit to produce regenerative braking on reverse rotation of said motor at a predetermined speed and limit the lowering speed of said carrier. 90
16. In a hoisting apparatus, the combination with a carrier of a drum and cable for hoisting the same, an electric motor for rotating said drum, a controller and electrical connections for said motor, and a governor driven by said motor cooperating with said controller for automatically producing regenerative braking on reversal of said motor to limit the lowering speed of said carrier. 95
17. In a hoisting apparatus, the combination with a carrier of a drum and cable for hoisting the same, an alternating current electric motor for driving said drum, and means cooperating with said motor on reversal thereof automatically to produce regenerative braking for maintaining a substantially constant lowering speed for said carrier. 100
18. In a hoisting apparatus, the combination with a carrier of a drum and cable for hoisting the same, an electric motor for rotating said drum, a brake for said drum, means cooperating with said motor on reversal thereof automatically to produce regenerative braking to limit the lowering speed of said carrier, and fluid-pressure responsive means for automatically applying said brake on reverse rotation of said drum above a predetermined speed. 105
19. In a hoisting apparatus, the combination with a carrier of a drum and cable for hoisting the same, an electric motor for rotating said drum, a brake for said drum; means including an electrical circuit, a switch therein, and a governor driven by said motor for automatically actuating said switch and producing regenerative braking to limit the lowering speed of said carrier on reverse rotation of said drum; and means operated by said governor for automatically applying said brake on reverse rotation of said motor above a predetermined speed. 110
20. In a hoisting apparatus, the combination with a carrier of a drum, a cable connecting the same, an electric motor for rotating said drum to hoist said carrier, an automatic brake cooperating with said drum to hold the carrier in elevated position, and means operable on release of said brake to limit lowering of said carrier to a substantially constant speed. 115
21. In a hoisting apparatus, the combination with a hoisting drum 13 of a carrier 7, a cable 9 connecting said carrier with said drum, an electric motor 85 for rotating said drum to hoist said carrier, means 51, 53 cooperating with said drum to hold said carrier in elevated position, and means 91 cooperating with said motor for automatically producing regenerative braking to limit the drop of said carrier to a predetermined speed on release of said holding means. 120
22. A hoisting apparatus comprising, in combination, a load-sustaining device, load-raising mechanism, a motor for driving said load-raising mechanism to hoist the load, circuit-controlling devices to provide for regenerative braking of the motor on lowering the load, a brake and a speed-responsive device with means for coordinately controlling thereby the brake and the circuit-controlling devices. 125
23. A hoisting apparatus comprising, in combination, a load-sustaining device, load-raising mechanism, a motor for driving said load-raising mechanism to hoist the load, circuit-controlling devices to provide for 130

- regenerative braking of the motor on lowering the load, and means to provide for a substantially constant lowering speed of the motor while on the regenerative braking circuit.
24. A hoisting apparatus comprising, in combination, a load-sustaining device, load-raising mechanism, a synchronous motor for driving said load-raising mechanism to hoist the load, circuit-controlling devices to provide for regenerative braking of the motor on the lowering of the load, and means for maintaining a substantially constant motor speed during regenerative braking.
- 10 25. A hoisting apparatus comprising, in combination, a load-sustaining device, load-raising mechanism, a synchronous motor for driving said load-raising mechanism to hoist the load, circuit-controlling devices to provide for regenerative braking of the motor on the lowering of the load, and a brake to maintain a substantially constant motor speed during regenerative braking.
- 15 26. A hoisting apparatus comprising, in combination, a load-sustaining device, load-raising mechanism, a motor for driving said load-raising mechanism to hoist the load, circuit-controlling devices to provide for regenerative braking of the motor on the lowering of the load and a brake with means to cause the same to automatically supplement the speed control of the motor during regenerative braking.
- 20 27. A hoisting apparatus comprising, in combination, a load-sustaining device, load-raising mechanism, an electric motor for driving said mechanism to raise the load devices for regeneratively breaking the motor on descent of the load, and a mechanical brake with means for automatically applying it in the event that excess speed is reached during regenerative breaking.
- 25 28. A hoisting apparatus comprising in combination, a load-sustaining device, load-raising mechanism, a synchronous electric motor for driving said mechanism to raise the load, devices for regeneratively breaking the motor on descent of the load effective when synchronous speed is reached, and a mechanical brake with means for automatically applying it when synchronous speed is exceeded during regenerative breaking.
- 30 29. A hoisting apparatus comprising in combination, a load-sustaining device, load-raising mechanism, an electric driving motor, a brake to hold the load when raised, devices for regeneratively breaking the motor on descent of the load, and devices to apply the brake during the regenerative breaking when an excess speed has been reached.
- 35 30. A hoisting apparatus comprising in combination, a load-sustaining device, load-raising mechanism, an electric driving motor, a regenerative breaking circuit for the motor, a controlling switch therefor, a speed controlled governor for moving said switch, a mechanical brake for holding the load when raised, and speed responsive means for applying the brake.
- In testimony whereof, I have signed my name to this specification.
- ALMON E. NORRIS.
